UNITED STATES PATENT OFFICE.

HARRY G. GRUBBS, OF ALLEGHENY, PENNSYLVANIA.

FLUSHING CUSPIDOR.

SPECIFICATION forming part of Letters Patent No. 678,481, dated July 16, 1901.

Application filed September 18, 1900. Serial No. 30,381. (No model.)

To all whom it may concern:

Be it known that I, HARRY G. GRUBBS, a citizen of the United States of America, residing at Allegheny, in the county of Allegheny and State of Pennsylvania, have invented certain new and useful Improvements in Flushing Cuspidors, of which the following is a specification, reference being had therein to the accompanying drawings.

10 This invention relates to certain new and useful improvements in flushing cuspidors, and has for its object the provision of novel means whereby the cuspidors are arranged stationary in the floor and constantly flush 15 or intermittently flush, as desired, so as to thoroughly cleanse the same at all times.

The herein-described invention is particularly adapted to be used for public buildings; and it consists of a stationary cuspidor arranged in the floor of the building, the same being connected to a water-supply pipe and a waste-pipe.

20 The invention further consists in the novel construction, combination, and arrangement 25 of parts, to be hereinafter more fully described, and specifically pointed out in the claims.

In describing the invention in detail, reference is had to the accompanying drawings, 30 forming a part of this specification, and where-in like numerals of reference indicate corresponding parts throughout the several views, in which—

Figure 1 is a perspective view of a section 35 of floor having arranged therein two of my improved cuspidors. Fig. 2 is a vertical sectional view of the same. Fig. 3 is a top plan view of the annular pipe arranged in the interior of the cuspidor, as will be hereinafter 40 more fully described.

In the drawings the reference-numeral 1 indicates the floor of the building, and 2 the joists of the floor. The reference-numeral 3 represents the body of the cuspidor, having 45 at its upper extremity a flange 4, which is countersunk in the floor and so arranged as to be flush with the same, the inner portion of said flange overhanging the inner wall of the spittoon. The said cuspidor is further 50 provided with an interior annular perforated pipe 5, connected to the supply-pipe 6 by means of the union 6' and nipple 6", Fig. 3,

which latter supports the ring 5 at a location underneath and adjacent to said overhanging flange, with a slight space intervening between the ring and wall of the spittoon, the bottom of said cuspidor communicating with a waste-pipe 7. The annular perforated pipe 5 is arranged interiorly in the upper portion of the cuspidor below the annular flange 4, 60 and the perforations are so arranged as to be inclined downwardly in order that when flushing the cuspidor the sides of the same will be thoroughly cleansed and all debris and other substances removed. A trap may 65 be arranged in said waste-pipe for the purpose of receiving large particles that may tend to clog the waste-pipe. The matter accumulating in said trap may be removed at any time.

70 From the above description it is thought the detail operation of my improved cuspidor can be readily understood and a further description thereof unnecessary.

The many advantages obtained by the use 75 of my improved cuspidor will be readily understood from the above description and reference to the accompanying drawings.

It will be noted that various changes may be made in the details of construction without departing from the general spirit of my invention.

Having thus fully described my invention, what I claim as new, and desire to secure by 85 Letters Patent, is—

A flushing spittoon comprising the body portion having an annular flange overhanging its inner wall and at the top thereof, a supply-pipe, a union mounted thereon, a hollow nipple secured to and communicating with 90 said union, a hollow annular perforated ring supported by said nipple within the spittoon and adjacent to said flange with a slight space intervening between said ring and the inner wall of the spittoon, and the waste-pipe with 95 which the lower portion of the spittoon is connected, as set forth.

In testimony whereof I affix my signature in the presence of two witnesses.

HARRY G. GRUBBS.
